UNITED STATES PATENT OFFICE.

WILLIAM J. MACKLE, OF ELIZABETH, NEW JERSEY, ASSIGNOR OF ONE-HALF TO PETER M. KLING, OF ELIZABETH, NEW JERSEY.

ROTARY ENGINE.

SPECIFICATION forming part of Letters Patent No. 716,642, dated December 23, 1902.

Application filed August 22, 1902. Serial No. 120,611. (No model.)

To all whom it may concern:

Be it known that I, WILLIAM J. MACKLE, a citizen of the United States, residing at Elizabeth, New Jersey, have invented certain new and useful Improvements in Rotary Engines, of which the following is a specification.

My invention relates to engines of the rotary type, and has for its object to provide an engine of simple construction and economical of steam consumption and in which the pressure of the steam itself maintains steam-tight joints between moving parts.

Further objects of my invention are to provide an engine of such construction that any pressure which would tend to impair the packing or open joints which should be steam-tight is reduced to a minimum, to provide moving parts of such construction that wear is automatically taken up, and to provide a piston of such construction that its contact with the cylinder is automatically preserved steam-tight and wear compensated for.

A construction of engine embodying my invention is illustrated in the accompanying drawings, in which—

Figure 1 is a vertical section transversely of the cylinder. Fig. 2 is a vertical section longitudinally of the cylinder. Fig. 3 is a top plan view of the piston. Figs. 4 and 5 are views showing details of various parts of the engine.

The same reference letters and numerals are applied to the same parts in the different views.

I have illustrated a simple form of engine consisting of a single main cylinder; but it is to be understood that other similar cylinders may be connected to the same shaft, thus making engines of multiple or compound type, as well as providing means for obviating dead-centers.

A indicates the casing or shell of the engine which is of such form as to provide a housing for moving parts as well as to form the body of the cylinder. This casing is provided with screw-threaded flanges B for the attachment of the cylinder-heads B' B². The cylinder-heads are provided with suitable apertured hubs to provide journals for the shaft T.

The joints between the casing and the cylin-

der-heads and also the hubs of the latter are provided with the usual steam-packing gaskets and packing-glands, respectively, to preserve them steam-tight.

Attached to the shaft T, so as to rotate therewith, is a hub E. In this hub is a steam port and channel 13, by which steam is fed to the cylinder from the steam-inlet 3 in the cylinder-head B'. Mounted in this hub is the piston Q. The piston is formed of flaring shape, as shown, being wider at its extremity than near its seat. It is loosely mounted in its seat, so as to allow of movement radially. The object of providing a piston of flaring shape and admitting of radial movement will be explained later. The face of the piston Q is provided with a marginal plate 16, of soft metal—such as, for instance, Babbitt metal—as clearly shown in Figs. 1 and 3 of the drawings. This marginal plate is adjustably secured to the face of the piston Q by means of an undercut plate 17, the beveled edges of which engage the beveled edges of the marginal plate, as shown in the drawings. The plate 17 is held on the piston-face by means of screws 18.

Mounted so as to have a slight sliding longitudinal movement on hub E are cone-pieces F' F². These cones may be retained in place and have their outward longitudinal movement limited by screw-threaded collars f f, which are secured on threaded shoulders formed on ends of hub E. These cones are provided with sloping or beveled inner faces accurately fitting against beveled faces, so as to form an angle bearing thereupon. The respective bearing-faces of the cylinder and the cones must be made to fit securely, so that when the cones are pressed into contact with cylinder-faces a steam-tight joint is formed. The outer ends of the cones F' F² are recessed to form steam-chests 2 2'. The steam-chests at each end of the cylinder communicate through channels 15 in the hub E. The steam-chests are preserved steam-tight by suitable packing interposed between the cylinder-heads and the cones. A suitable cut-off J is provided in the end hub E, by which the admission of steam to the cylinder is regulated. This cut-off is held in position by pins 100

I in cylinder-head B', so as to allow of longitudinal movement. The cut-off may be regulated to work the engine expansively.

Above the cylinder is arranged a casing C, 5 inclosing the actuating device for fulcrum or abutment G. In the machine illustrated this actuating device consists of a cylinder 4, provided with piston L, to which is attached rod K. At the lower end of rod K is attached 10 fulcrum G, which enters the cylinder and at the limit of its downward movement abuts against hub E, so as to form a tight joint therewith. At the limit of the upward movement fulcrum G is withdrawn from the cylinder, so as to permit piston Q to pass by in its revolutions. Piston-rod K is guided in its movements through packing-glands H and O, the latter being conveniently carried by a centrally-apertured plate D, screwed onto the 15 top of the cylinder.

The fulcrum or abutment G is constructed, as shown in Fig. 4 of the drawings, of two members 19 and 19^a, provided with mating shoulders 20 20^a. The members 19 19^a are 20 secured together by means of a screw 21, which passes through a slot in the member 19^a and is screwed into the member 19, so that member 19 has a slight vertical longitudinal play with respect to the member 19^a. The 25 shoulders 20 20^a on the respective members form a cam-surface to force the members apart and automatically cause a tight joint between the fulcrum or abutment and the walls of its aperture, through which it reciprocates.

30 Cylinder 4 is provided with a packing-gland N for the passage of the piston-rod K and with a cap P. A spring M is provided beneath piston L, exerting an upward pressure thereon for the purpose of keeping fulcrum G in a 35 raised position out of the cylinder 1 and of the path of piston Q when the engine is not in operation.

Within the walls of cylinder-casings C and A, arranged as shown in the drawings, are 40 suitable steam passages and ports 9, 10, 11, and 12, by means of which steam is admitted at the proper times to and from cylinder 4. The admission of steam to these passages is controlled by the rotations of the cones F' 45 and F², which are provided with steam-passages 5, 6, 7, and 8, so arranged as to come into communication with passages 9, 10, 11, and 12 at and for the proper time to actuate the fulcrum G. The arrangement of these 50 passages will be understood from the following description of the operation of the engine. Steam being admitted at the inlet 3 into steam-chests 2 2' enters the cylinder through passage 13, the entry to which is controlled 55 by cut-off plate J. Simultaneously the steam enters channel 5 in cone F', which communicates with steam-chest 2, as shown in dotted lines. Passage 5 is of such length as to maintain communication with passage 9 for such 60 a period of time as will keep fulcrum G in its depressed position within the cylinder, as shown in Fig. 1, until it is required to be

raised out of the path of piston Q. When piston Q has reached the point when it is about to pass fulcrum G, passage 7 in cone F² comes into communication with steam-chest 2' 2' and passage 11, and thus admits steam to the lower side of piston L, thus forcing the piston to raise fulcrum G out of the path of piston Q. It will be apparent that 75 passage 7 in cone F² is much shorter than passage 5, since fulcrum G is required to be raised for a much shorter period of time than it is required to be depressed. The exhaust from the lower end of cylinder 4 is through 80 passage 10 and channel 6 in the cone F² to the exhaust-port 14, with which it communicates by lateral passage in the engine-casing. The exhaust from the upper end of cylinder 4 is through passage 10^a to channel 8 in the 85 cone F', which communicates through a lateral branch or passage with exhaust-port 14.

Although I have described and shown the actuation of fulcrum G by means of steam-pressure, I may, if desired, actuate the same 90 by means of a cam or eccentric and pitman connected with the main shaft, for instance. I may also use other fluid-pressure than steam.

An important feature of my invention, as 95 above indicated, is the angular bearing-faces of cones F' F², which, together with the sloping faces of the cylinder upon which they bear and the longitudinal movement permitted to the cones, automatically take up 100 all wear. The steam-pressure in the steam-chests upon the outer surfaces of the cones keeps the cones in close contact with the cylinder-faces. The angle of slope of the cone-faces and cylinder-faces may be of any desired 105 degree to accomplish the best results. I have found that the best results are secured when the angle of slope is greater than forty-five degrees with reference to the shaft.

Another advantage which my form of construction confers is that the surface of the cones exposed to steam-pressure from the interior of the cylinder is much smaller than that exposed to the exterior steam-pressure from the steam-chests. This obviates all tendency of the cones to move outwardly by reason of the pressure from the outside being in excess of that from within the cylinder. This not only insures a tight joint between the cone and cylinder faces, but the pressure from 110 the interior of the cylinder counteracts the pressure from the exterior and greatly reduces the friction and binding between the faces. By having the interior of the cylinder of the form shown in the drawings—that is, of a 115 somewhat-globular form, the cross-sectional area on the median line greater than the cross-sectional area of its end openings—the interior pressure on the cone-pieces is reduced, thus still further maintaining the disparity 120 between the outer and inner pressure on the cone-pieces.

It will be seen that by regulating the amount of steam applied to the steam-chests the dif-

ference in pressure on the outer and inner faces of the cones may be adjusted so as to reduce the friction between the cylinder and cone faces to a minimum, while at the same time preserving a steam-tight joint.

5 The form and manner of mounting of my piston, as before intimated, is an important feature of my invention. By reason of its flaring shape and its longitudinal or radial 10 play in its seat the pressure of the steam upon its sloping face tends to force it outwardly against the cylinder-wall, thus preventing any leakage of steam past its extremity. The centrifugal force developed during 15 the running of engine also tends to throw the piston outwardly against the cylinder-wall. By forming the face of the piston with a marginal plate of soft metal engaged by the plate 17 the pressure of the steam upon said plate 20 17 tends to press outwardly the soft-metal plate 16 against the walls of the cylinder, thus automatically insuring a steam-tight joint around the edges of the piston. The plate 17 being attached to the piston by means 25 of a screw, as shown, all wear of the marginal plate 16 may be taken up.

The abutment 19, being constructed as shown in Fig. 4, automatically forms a steam-tight joint at the moment it comes into action.

30 At every downward thrust its member 19 strikes the hub E, causing its shoulder 20 to engage with the shoulder 20^a of its mating member, and thereby force the two members apart to insure a steam-tight joint around the 35 sides of the abutment. On the retreat of the abutment G to allow the piston Q to pass the same the member 19 drops, and thus relieves the abutment of friction in its reciprocation through the cylinder-body.

40 Thus it will be seen that an engine constructed according to my invention possesses numerous features of advantage. Its working joints are automatically maintained steam-tight, thus insuring economy of steam consumption. Wear is taken up without the 45 need of inspecting and adjustment of inaccessible parts.

Having thus described my invention, the following is what I claim as new therein and 50 desire to secure by Letters Patent:

1. In a rotary engine, a steam-cylinder having at its ends sloping bearing-faces, cone-pieces mounted to close the ends of said cylinder with their sloping faces coincident with 55 the sloping bearing-faces of the cylinder, said cone-pieces being movable toward and from said cylinder and having steam-chests at their outer ends.

2. In a rotary engine, a steam-cylinder having at its ends outwardly-sloping bearing-faces, cone-pieces mounted to close the ends of said cylinder with their sloping faces coincident with the sloping bearing-faces of the cylinder, said cone-pieces being movable to- 60

ward and from said cylinder and having steam-chests at their outer ends.

3. In a rotary engine, a steam-cylinder hav-

ing at its ends sloping bearing-faces, cone-pieces mounted to close the ends of said cylinder with their sloping faces coincident with 70 the sloping bearing-faces of the cylinder, said cone-pieces being movable toward and from said cylinder and having steam-chests at their outer ends, the cone-pieces having greater area exposed to steam-pressure from 75 the steam-chests than is exposed to pressure from within the cylinder.

4. In a rotary engine, a cylinder having its interior of greater cross-sectional area at the median line thereof than at the ends thereof, 80 and having its ends formed with sloping bearing-faces, cone-pieces mounted to close the ends of said cylinder with their sloping faces coincident with the sloping bearing-faces of the cylinder, said cone-pieces being movable 85 toward and from said cylinder and having steam-chests at their outer ends.

5. In a rotary engine, a steam-cylinder having its interior of greater cross-sectional area at the median line thereof than at the ends thereof, 90 and having its ends formed with outwardly-sloping bearing-faces, cone-pieces mounted to close the ends of said cylinder with their sloping faces coincident with the sloping bearing-faces of the cylinder, said 95 cone-pieces being movable toward and from said cylinder and having steam-chests at their outer ends.

6. In a rotary engine having its interior of greater cross-sectional area at the median line 100 thereof than at the ends thereof, and having its ends formed with sloping bearing-faces, cone-pieces mounted to close the ends of said cylinder with their sloping faces coincident with the sloping bearing-faces of the cylinder, 105 said cone-pieces being movable toward and from said cylinder and having steam-chests at their outer ends, the cone-pieces having greater area exposed to steam-pressure from the steam-chests than is exposed to 110 pressure from within the cylinder.

7. In a rotary engine, a cylinder, a shaft passing through said cylinder, a piston carried by said shaft, a fulcrum reciprocated into and out of said cylinder, said fulcrum when with- 115 in the cylinder forming with said piston a closed steam-chamber, and means to hold said fulcrum out of the path of said piston when the engine is not in operation.

8. In a rotary engine, the cylinder, a shaft 120 passing through said cylinder, a piston carried by said shaft, a fulcrum reciprocated into and out of said cylinder, an auxiliary cylinder to operate said fulcrum, a spring interposed between the lower face of the piston 125 within the said auxiliary cylinder and lower cylinder-head thereof, said spring exerting upward pressure upon said auxiliary piston to hold the fulcrum out of the path in the main cylinder when the engine is not in op- 130 eration.

9. In a rotary engine, a main cylinder, a shaft passing through the same, a piston carried by said shaft, a fulcrum reciprocated into

and out of said cylinder to form with said piston a closed steam-chamber, an auxiliary cylinder to operate the said fulcrum, cone-pieces mounted on the shaft of said main cylinder 5 and having steam-chests at their outer ends, ports in said cone-pieces communicating with said steam-chests and said main cylinder, and other ports and passages within said cone-pieces communicating with said steam-chests 10 and said auxiliary cylinder.

10. In a rotary engine, a cylinder, a shaft passing through the same, a hub mounted on said shaft, cone-pieces mounted on said shaft to close the ends of the cylinder, steam-chests 15 at the outer ends of said cone-pieces, passages within the hub connecting the steam-chest of one cone-piece with the steam-chest of the other cone-piece.

11. In a rotary engine, a steam-cylinder 20 having at its ends sloping bearing-faces, a shaft passing through said cylinder, cone-pieces mounted on said shaft to close the ends of said cylinder with their sloping faces coincident with the sloping bearing-face of the 25 cylinder, said cone-pieces being movable longitudinally of the shaft, steam-chests at the outer ends of said cone-pieces, a hub mounted on said shaft, passages within the hub connecting the steam - chest of one cone-piece with the steam-chest of the other cone-piece.

12. In a rotary engine, a cylinder, a shaft passing through the same, a piston carried by said shaft and capable of radial movement 35 with relation thereto, said piston having its pressure-face inclined to the direction of pressure, the inclination of said face being such that the pressure of steam thereon will tend to force the piston radially outward.

40 13. In a rotary engine, a cylinder, a shaft passing through the same, a hub mounted on said shaft, a piston seated in said hub and ca-

pable of radial movement therein, said piston having its pressure-face inclined to the direction of steam-pressure, the inclination of said 45 face being such that the pressure of steam thereon will tend to force the piston radially outward.

14. A piston having packing on the pressure-face thereof, and means co-operating with 50 said packing and responsive to the steam-pressure thereof to press said packing toward the cylinder-walls.

15. A piston having a marginal packing-plate on its pressure-face, a plate engaging 55 said packing-plate to retain it in position, both said plates having beveled engaging edges.

16. A piston having a marginal packing-plate on its pressure-face, said plate having beveled edges, a retaining-plate having undercut edges engaging said packing-plate, and adjustable means to cause the retaining-plate 60 to press the packing-plate toward the cylinder-walls.

17. A piston having a marginal packing-plate on its pressure-face, said plate having beveled edges, a retaining-plate having undercut edges engaging said packing-plate, and adjustable means to cause the retaining-plate 70 to press the packing-plate toward the cylinder, said retaining-plate tending to press the packing-plate toward the cylinder-walls when the piston is subjected to steam-pressure.

18. A piston having on its pressure-face a marginal packing-plate of antifriction metal 75 provided with beveled edges, a retaining-plate having undercut beveled edges engaging said packing-plate, means to adjust the engagement of the two plates and to take up wear of the packing-plate.
